United States Patent Office

Des. 185,397
Patented June 2, 1959

185,397

AUTOMOBILE WASHING UNIT

Max C. Thompson, Arcadia, Calif.

Application April 15, 1957, Serial No. 45,740

Term of patent 14 years

(Cl. D49—1)

Fig. 4.

Fig. 5.

Fig. 1 is a front elevational view of an automobile washing unit showing my new design;

Fig. 2 is a view in rear elevation of the unit;

Fig. 3 is a side elevational view thereof;

Fig. 4 is a vertical section taken substantially on line 4-4 of Fig. 2; and

Fig. 5 is a horizontal section taken substantially on line 5-5 of Fig. 4.

The dominant features of the design reside in the portions shown in full lines.

I claim:

The ornamental design for an automobile washing unit, as shown and described.
